UNITED STATES PATENT OFFICE

138,317

DESIGN FOR A HOUSING FOR A VEHICLE LIGHT

Eric B. Hallman, Philadelphia, Pa., assignor to
Electric Service Supplies Company, Philadelphia, Pa., a corporation of Pennsylvania

Application March 21, 1944, Serial No. 112,976

Term of patent 7 years

(Cl. D48—32)

To all whom it may concern:

Be it known that I, Eric B. Hallman, a citizen of the United States and a resident of Philadelphia, county of Philadelphia, State of Pennsylvania, have invented a new, original, and ornamental Design for Housing for a Vehicle Light, of which the following is a specification, reference being had to the accompanying drawing, forming a part thereof, wherein:

Figure 1 is a front elevational view of a housing for a vehicle light showing my new design;
Figure 2 is an end elevational view thereof; and
Figure 3 is a vertical transversely sectional view thereof.

I claim:

The ornamental design for a housing for a vehicle light, as shown.

ERIC B. HALLMAN.
